UNITED STATES PATENT OFFICE

109,538

DESIGN FOR A RAILWAY PASSENGER VEHICLE

Clifford Brooks Stevens, Milwaukee, Wis.

Application December 18, 1937, Serial No. 73,696

Term of patent 14 years

To all whom it may concern:

Be it known that I, Clifford Brooks Stevens, a citizen of the United States, residing at Milwaukee, in the county of Milwaukee and State of Wisconsin, have invented a new, original, and ornamental Design for a Railway Passenger Vehicle, of which the following is a specification, reference being had to the accompanying drawing, forming part thereof.

Figure 1 is a side elevational view of a railway passenger vehicle showing my new design;

Figure 2 is a rear elevational view thereof; and Figure 3 is a front elevational view thereof. Both sides of the vehicle have the same appearance as shown in Figure 1.

I claim:

The ornamental design for a railway passenger vehicle, as shown and described.

CLIFFORD BROOKS STEVENS.
